UNITED STATES PATENT OFFICE.

VERNER J. WAHLSTROM, OF NEW YORK, N. Y.

CLUTCH.

No. 870,206.

Specification of Letters Patent.

Patented Nov. 5, 1907.

Application filed April 6, 1907. Serial No. 366,696.

To all whom it may concern:

Be it known that I, VERNER J. WAHLSTROM, a citizen of the United States, and resident of New York, in the county of Kings and State of New York, have invented a new and useful Clutch, of which the following is a specification.

This invention relates to an improvement in clutches, and it is one of the objects thereof to provide a device of this character in which a pulley or other normally loose member may be temporarily secured to a shaft by the action of a wedging roller and coöperating member.

With this and other objects in view, the invention consists in certain constructions and combinations which will be hereinafter fully described and then specifically pointed out in the claims hereunto appended.

In the accompanying drawings which form a part of this specification and in which like characters of reference indicate the same parts, Figure 1 is a side elevation of a device constructed in accordance with the invention; Fig. 2 is an end elevation, partly in section, of the structure shown in Fig. 1; Fig. 3 is a sectional view taken on the line 3—3 in Fig. 2; and Fig. 4 is a detail view of one of the operating members.

In carrying the invention into effect, there is provided a shaft 1 of any approved form, a ring 2 loosely mounted concentric with the shaft, and a roller or plurality of rollers 3 interposed between the ring and shaft. When a plurality of rollers are used, they will be symmetrically arranged between the ring and shaft for the purpose of equalizing the strain. In the best constructions and as shown, two rollers diametrically disposed, are used. The inner periphery of the ring is provided with a cam surface 4, or when a plurality of rollers are used, with a plurality of cam surfaces, contacting with the roller or rollers so that when a relative rotary movement of the ring and shaft is set up, these cam surfaces will cause the rollers to move inwardly and become wedged between the ring and shaft, thereby effecting the clutching of the ring to the shaft.

Means are provided for producing the relative rotary movement just referred to and this means may vary widely in construction. In the best constructions, however, this means will be spring actuated, and as shown, consists of spring plungers 5 interposed between the ring and abutments 6 located outside the ring. It will be seen that in the device illustrated the plungers are carried by the ring and bear against the abutments, although it is obvious that other constructions might be used. The abutments may be variously supported. As shown, they are rigidly connected with a hub 7 interposed between the ring and shaft, the connection being effected by means of a web 8 which forms a part of a pulley 9. The rollers are positioned and carried by the hub 7 which is provided with a series of pockets

10 extended therethrough, this construction serving to retain the rollers in symmetrical position.

A sleeve 11 may be fastened on the shaft for the purpose of preventing excessive wear thereof due to the action of the rollers, the latter being, when the sleeve is used, wedged between the ring and sleeve.

Means are provided for producing a positive reverse movement of the ring and shaft whereby the clutch is thrown out of action, and this means may vary widely in construction. In the best constructions and as shown, the ring 2 is provided with studs 12 which are engaged by cam surfaces 13 formed on rods 14 slidably mounted in the hub 7 before referred to. The cam surfaces 13 are so arranged that when the rods are given a longitudinal movement in one direction, the studs 12, and consequently the ring 2, will be rotated against the stress of the spring plungers 5. When the rods are moved in the opposite direction, the studs will be released and the spring plungers permitted to act to throw the clutch into action.

Means are provided for simultaneously moving the rods and this means may vary in construction. In the best constructions and as shown, the rods 14 are provided with recessed heads 15 engaged by a collar 16 slidably mounted on the shaft 1 and having an annular channel 17 formed therein for engagement with a suitable operating yoke, not shown.

Changes and variations may be made in the structure by which the invention is carried into effect. The invention, therefore, is not to be restricted to the precise details of the structure shown and described.

What is claimed is:

1. In a clutch, the combination with a shaft, of a ring loosely mounted concentric with the shaft, a roller interposed between the ring and shaft, a cam surface on the inner periphery of the ring contacting with the roller, and spring actuated means for producing a relative rotary movement of the ring and shaft, substantially as described.

2. In a clutch, the combination with a shaft, of a ring loosely mounted concentric with the shaft, a roller interposed between the ring and shaft, a cam surface on the inner periphery of the ring contacting with the roller, spring actuated means for producing a relative rotary movement of the ring and shaft, and means for producing a positive reverse movement, substantially as described.

3. In a clutch, the combination with a shaft, of a ring loosely mounted concentric with the shaft, a plurality of rollers symmetrically arranged between the ring and shaft, cam surfaces on the inner periphery of the ring contacting with the rollers, and spring actuated means for producing a relative rotary movement of the ring and shaft, substantially as described.

4. In a clutch, the combination with a shaft, of a ring loosely mounted concentric with the shaft, two diametrically disposed rollers between the ring and shaft, cam surfaces on the inner periphery of the ring contacting with the rollers, and spring actuated means for producing a relative rotary movement of the ring and shaft, substantially as described.

5. In a clutch, the combination with a shaft, of a ring

loosely mounted concentric with the shaft, a plurality of rollers disposed between the ring and shaft, cam surfaces on the inner periphery of the ring contacting with the rollers, spring actuated means for producing a relative rotary movement of the ring and shaft, and means engaging the ring for producing a positive reverse movement, substantially as described.

6. In a clutch, the combination with a shaft, of a ring loosely mounted concentric with the shaft, a plurality of rollers disposed between the ring and shaft, cam surfaces on the inner periphery of the ring contacting with the rollers, spring actuated means for producing a relative rotary movement of the ring and shaft, and means including studs fast in the ring and connections for producing a positive reverse movement, substantially as described.

7. In a clutch, the combination with a shaft, of a ring loosely mounted concentric with the shaft, a plurality of rollers disposed between the ring and shaft, cam surfaces on the inner periphery of the ring contacting with the rollers, spring actuated means for producing a relative rotary movement of the ring and shaft, and means including studs fast in the ring and connections mounted to slide in a direction parallel to the axis of the shaft for producing a positive reverse movement, substantially as described.

25. 8. In a clutch, the combination with a shaft, of a ring loosely mounted concentric with the shaft, a plurality of rollers disposed between the ring and shaft, cam faces on the inner periphery of the ring contacting with the rollers, spring actuated means for producing a relative rotary movement of the ring and shaft, studs fast in the ring, rods having cam faces contacting with the studs and mounted to slide in a direction parallel to the axis of the shaft, and a collar sliding on the shaft and engaging the rods to move them simultaneously, substantially as described.

9. In a clutch, the combination with a shaft, of a sleeve fast on the shaft, a ring loosely mounted concentric with the shaft, a plurality of rollers disposed between the ring and sleeve, cam surfaces on the inner periphery of the ring contacting with the rollers, and spring actuated means for producing a relative rotary movement of the ring and sleeve, substantially as described.

10. In a clutch, the combination with a shaft, of a sleeve fast on the shaft, a ring loosely mounted concentric with the sleeve, a hub disposed between the ring and sleeve, a plurality of rollers carried by the hub, cam surfaces on the inner periphery of the ring contacting with the rollers, and spring actuated means for producing a relative rotary movement of the ring and sleeve, substantially as described.

11. In a clutch, the combination with a shaft, of a sleeve fast on the shaft, a ring loosely mounted concentric with the sleeve, a plurality of rollers disposed between the ring and sleeve, cam surfaces on the inner periphery of the ring contacting with the rollers, abutments outside the ring, and means interposed between the ring and abutments for producing a relative rotary movement of the ring and sleeve, substantially as described.

12. In a clutch, the combination with a shaft, of a sleeve fast on the shaft, a ring loosely mounted concentric with the sleeve, a plurality of rollers disposed between the ring and sleeve, cam surfaces on the inner periphery of the ring contacting with the rollers, abutments outside the ring, and spring plungers interposed between the ring and abutments for producing a relative rotary movement of the ring and sleeve, substantially as described.

13. In a clutch, the combination with a shaft, of a sleeve fast on the shaft, a ring loosely mounted concentric

with the sleeve, a plurality of rollers disposed between the ring and sleeve, cam surfaces on the inner periphery of the ring contacting with the rollers, abutments outside the ring, and spring plungers mounted in the ring and bearing against the abutments for producing a relative rotary movement of the ring and sleeve, substantially as described.

14. In a clutch, the combination with a shaft, of a sleeve fast on the shaft, a ring loosely mounted concentric with the sleeve, a plurality of rollers disposed between the ring and sleeve, cam surfaces on the inner periphery of the ring contacting with the rollers, abutments outside the ring, spring plungers interposed between the ring and abutments for producing a relative rotary movement of the ring and sleeve, and means for producing a positive reverse movement, substantially as described.

15. In a clutch, the combination with a shaft, of a sleeve fast on the shaft, a ring loosely mounted concentric with the sleeve, a hub interposed between the ring and sleeve, a plurality of rollers carried by the hub, cam surfaces on the inner periphery of the ring contacting with the rollers, abutments rigidly connected with the hub and lying outside the ring, and spring plungers interposed between the ring and abutments for producing a relative rotary movement of the ring and sleeve, substantially as described.

16. In a clutch, the combination with a shaft, of a sleeve fast on the shaft, a ring loosely mounted concentric with the sleeve, a pulley having a hub interposed between the ring and sleeve, a plurality of rollers carried by the hub, cam surfaces on the inner periphery of the ring contacting with the rollers, abutments formed on the pulley outside the ring, and spring plungers interposed between the ring and abutments for producing a relative rotary movement of the ring and sleeve, substantially as described.

17. In a clutch, the combination with a shaft, of a sleeve fast on the shaft, a ring loosely mounted concentric with the sleeve, a pulley having a hub provided with a series of pockets extending therethrough and interposed between the ring and sleeve, a plurality of rollers mounted in the pockets, cam surfaces on the inner periphery of the ring contacting with the rollers, abutments formed on the pulley outside the ring, and spring plungers interposed between the ring and abutments for producing a relative rotary movement of the ring and sleeve, substantially as described.

18. In a clutch, the combination with a shaft, of a sleeve fast on the shaft, a ring loosely mounted concentric with the sleeve, a pulley having a hub provided with a series of pockets extending therethrough and interposed between the ring and sleeve, a plurality of rollers mounted in the pockets, cam surfaces on the inner periphery of the ring contacting with the rollers, abutments formed on the pulley outside the ring, spring plungers interposed between the ring and abutments for producing a relative rotary movement of the ring and sleeve, studs in the ring, rods having cam surfaces engaging the studs, and a collar sliding on the shaft and engaging the rods to operate them to produce a positive reverse movement, substantially as described.

In testimony whereof, I have signed my name to this specification in the presence of two subscribing witnesses.

VERNER J. WAHLSTROM.
